UNITED STATES PATENT OFFICE

2,576,537

SUBMERSIBLE TYPE INSULATED CONNECTOR

Julian Rogoff, New Rochelle, N. Y., assignor to Burndy Engineering Company, Inc., a corporation of New York

Application July 29, 1947, Serial No. 764,323

4 Claims. (Cl. 174—87)

1

My invention relates to insulated electrical connectors suitable for use in underground electrical distribution systems.

In underground electrical secondary distribution systems, connections in the cables must be completely insulated in a watertight manner resistant to the deteriorating influences of oils, sewage, gases, etc. which may contaminate the water ordinarily found in underground manholes and vaults. The task of insulating such connections is usually laborious and time consuming and the final insulated joints are of uncertain quality being entirely dependent on the skill of the cable splicer.

Among the objects of my invention are to provide a completely insulated and water-tight connector for a plurality of conductor connections wherein all parts needed for establishing the clamping connection to an insulated cable are self contained; to provide such a connector wherein the aforesaid parts may accommodate a range of cable sizes; wherein the clamping parts are provided in sealed recesses in the insulation and separately positioned from and readily accessible to the cable inserting recess; in which the clamping recess and the cable inserting recess may be quickly sealed after installation of the cable; and wherein the cables may be compactly installed to the connector, side by side in a minimum of space and the electrical connections established by the clamping parts with maximum facility despite the compact arrangement of the cables.

I accomplish these and other objects and obtain my new results as will be apparent from the device described in the following specification, particularly pointed out in the claims, and illustrated in the accompanying drawing, in which:

Fig. 1 is a front elevational view of my sealed connector provided with extending threaded stud for mounting to an apertured wall.

Fig. 2 is a sectional view of the connector complete with connections, and mounted to an apertured wall.

Fig. 3 is a front elevational view of a similar connector and provided with multiple outlet connections one of which is shown in section.

Fig. 4 is a side elevation of the same.

Referring more in detail to the drawing, and especially Figs. 1 and 2, reference numeral 10 designates the metal body section provided with a threaded conductor securing recess or aperture 11 for receiving a threaded clamping or pressure bolt 12, and transversely positioned thereto, a conductor-supporting recess 13 for receiving a bared

2

end 14 of an insulated conductor 15 provided with insulation 16.

A stud bolt 17 may extend longitudinally of the connector body 10, to form attaching means through an aperture 18 of a container wall 19. The entire connector body 10 is covered with a layer of insulation 20 having recessed tubular shoulders 21, 22, and 23, for permitting access to the recesses 11 and 13, and for encircling a portion of the threaded stud 17 respectively.

Caps 24 and 25 are employed for closing the recesses as shown in Figures 1 and 2. The threaded clamping bolt 12 is provided at its clamping end with an apertured pressure plate 26 through which aperture 27, the end 28 of the bolt 12 extends and which end is peened over to form a swivel, permitting the plate to be tightened to the conductor without rotation when the clamping bolt is turned. The remaining end 29 of the bolt 12 is preferably provided with a hexagonal type recess 29' to permit tightening with a "hex" type wrench shown in dot-dash lines 29b. Thus, when the bared end 14 of the conductor is inserted into the recess 13, the clamping bolt when tightened forces the pressure plate against the conductor, securing it to the connector body.

Cap or plug 24 may be made of hard insulation material provided with a tapering neck 30, and a threaded recess 31 for engaging the extending threaded end 29 of the bolt 12. The tubular shoulder 21 may be correspondingly tapered as at 32 to permit the tapered neck 30 of the cap 24 to be pressed tightly thereto, sealing the clamping bolt aperture against leakage.

The tubular shoulder 22 is of sufficient length to permit a pressure clamp 33 to be applied and tightened thereon sealing the soft insulation of the connector body to the insulation of the conductor.

Cap or plug 25 may be formed with plug end 34 to fit tightly into the recess of tubular shoulder 22, and adhesively sealed thereto to prevent leakage. The adhesive seal, may be broken when the cap is removed for installing the conductor

45 therein.

When the device is mounted to a container as for instance, the wall of a transformer, the extending threaded stud 17 with insulation shoulder 23 is inserted through the aperture 18 of the container wall 19, and a compressible type of insulating washer 40 inserted over the stud, with electric terminal 41 inserted thereafter. Nut 42 completes the assembly sealing and securing the insulated connector body 10 to the container wall, and simultaneously establishing a path of

current flow to the terminal 41. The soft insulation 20 acts as a sealing and insulating washer between the connector body and the container wall, washer 40 assisting in this function inside the container wall, the insulation neck 23 insulating the stud from the container wall.

Thus a double insulating and leak-proof seal is created, the connector rigidly secured, and simultaneously the current is transmitted from one conductor to the other.

In place of the stud, any other type of securing and/or electrical transmitting means may be employed.

In Figs. 3 and 4, a multiple outlet type of connector employing my invention, is shown, wherein corresponding parts of the device illustrated in Figs. 1 and 2, are identified with the same reference number, adding the postscript "a." The conductor outlets 51 to 55 inclusive correspond to clamping outlets 56 to 60 inclusive. Outlet 53 of the connector body 10a and the clamping bolt 12a are shown in section, with pressure plate 26a in plain view. Outlet 55 is illustrated with the pressure clamp 33a encircling tubular shoulder 22a, the two ends of the clamp being tightly bolted as at 61a. The hexagonal recess 29a in the clamping bolt 12a is shown in clamping outlet 59.

It will be noted that by my arrangement of the clamping bolts, I am able to mount the conductor outlets closely together since there is no need to use a wrench required by the cone type fittings hitherto employed concentrically mounted about the conductor ends. This is of particular advantage in underground manholes, handholes, and vaults, which are usually crowded.

I am thus able to obtain an insulated watertight connection with a minimum of skilled labor required for the tapering type of conductor seal hitherto employed and with less dependence on the quality of the workmanship.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained, and new results accomplished, as it is obvious that the particular embodiments here shown and described are only some of the many that can be employed to attain these objects and accomplish these results.

What I claim and desire to secure by Letters Patent is as follows:

1. An electrical connector for transmitting current from one conductor to another comprising a metallic body member having a conductor securing recess and a conductor supporting recess transversely positioned with respect thereto and connecting therethrough, an insulating cover for said connector body provided with an opening adjacent each recess in the connector body, plugs of insulating material positioned in the recesses, said body member being threaded about said conductor securing recess and provided with a pressure screw mounted beneath the insulating plug positioned in the conductor securing recess for mechanically and electrically securing the metal end of an insulated conductor to be positioned in the conductor supporting recess, the plug for the

conductor securing recess having threaded means for threaded engagement with the pressure screw to enable the plug to be tightly secured thereto and making a seal with the insulating cover and means for mechanically sealing the insulating cover to the plug positioned in the conductor receiving recess.

2. An electrical connector for transmitting current from one conductor to another comprising a metallic body member having a conductor securing recess and a conductor supporting recess transversely positioned with respect thereto and connecting therethrough, an insulating cover for said connector body provided with an opening adjacent each recess in the connector body, plugs of insulating material positioned in the recesses, said body member being threaded about said conductor securing recess and provided with a pressure screw mounted beneath the insulating plug positioned in the conductor securing recess for mechanically and electrically securing the metal end of an insulated conductor to be positioned in the conductor supporting recess, the insulating cover being provided with an extending tubular portion about the conductor supporting recess, the plug for the conductor securing recess being threaded for securing a sealed connection to the insulating cover, the other plug for the conductor supporting recess being provided with an inwardly extending neck positioned inside the tubular portion of the insulating cover, and means for mechanically sealing the tubular shoulder about the neck of said other plug.

3. An electrical connector for transmitting current from one conductor to another comprising a metallic body member having a conductor securing recess and a conductor supporting recess transversely positioned with respect thereto and connecting therethrough, an insulating cover for said connector body provided with an opening adjacent each recess in the connector body, plugs of insulating material removably positioned within the recesses, means for securing and sealing the plugs to the insulating cover, means within the conductor securing recess for clamping the metal end of an insulated conductor to be positioned within the conductor supporting recess, said connector body provided with a shoulder and a threaded metal stud extending therefrom for mounting the connector to a supporting structure, said insulating cover constructed of a resilient material and extending around the shoulder and between the shoulder and supporting structure for sealing the connector thereto, when the threaded stud is engaged on the opposite side of the supporting structure.

4. An electrical connector for transmitting current from one conductor to another comprising a metallic body member having a conductor securing recess and a conductor supporting recess transversely positioned with respect thereto and connecting therethrough, an insulating cover for said connector body provided with an opening adjacent each recess in the connector body, plugs of insulating material removably positioned within the recesses, means for securing and sealing the plugs to the insulating cover, means within the conductor securing recess for clamping the metal end of an insulated conductor to be positioned within the conductor supporting recess, said connector body provided with a threaded metal stud extending therefrom for securing the connector to a supporting structure, said insulating cover extending around said stud and partially along its length beyond said insulating

cover for insulating the connector from the supporting structure.
